US0D1077988S

(12) **United States Design Patent** (10) **Patent No.:** **US D1,077,988 S**
(45) **Date of Patent:** **** Jun. 3, 2025**

(54) **FAUCET SPOUT**

- (71) Applicant: **Kohler Co.**, Kohler, WI (US)
(72) Inventors: **Erin L. Hoover**, New York, NY (US);
William C. McKeone, Sheboygan, WI (US)
(73) Assignee: **KOHLER CO.**, Kohler, WI (US)
(**) Term: **15 Years**
(21) Appl. No.: **29/942,110**
(22) Filed: **May 14, 2024**

Related U.S. Application Data

- (62) Division of application No. 29/770,532, filed on Feb. 12, 2021, now Pat. No. Des. 1,032,787.

(57) **CLAIM**

The ornamental design for a faucet spout as shown and described.

DESCRIPTION

FIG. 1 is a perspective view of the claimed design; FIG. 2 is a top view of the claimed design shown in FIG. 1; FIG. 3 is a bottom view of the claimed design shown in FIG. 1; FIG. 4 is a side view of the claimed design shown in FIG. 1; FIG. 5 is another side view of the claimed design shown in FIG. 1; FIG. 6 is a front view of the claimed design shown in FIG. 1; and, FIG. 7 is a rear view of the claimed design shown in FIG. 1.

The broken lines are included for the purpose of illustrating portions of the article and form no part of the claimed design. Broken lines formed by equal length dashes show unclaimed portions of the design.

1 Claim, 6 Drawing Sheets
